(57) **CLAIM**

The ornamental design for an open compression-type coaxial cable connector, as shown and described.

DESCRIPTION

FIG. 1 is a front perspective view of an open compression-type coaxial cable connector showing our new design; FIG. 2 is a back perspective view thereof; FIG. 3 is a top plan view thereof, the bottom plan view being a mirror image thereto; FIG. 4 is a left side elevation view thereof, the right side elevation view being a mirror image thereto; FIG. 5 is an enlarged front elevation view thereof; and, FIG. 6 is an enlarged back elevation view thereof.

The broken line portion of the figure drawings is included for the purpose of illustrating environment and forms no part of the claimed design.
